US0D1067959S

(12) **United States Design Patent** (10) **Patent No.:** **US D1,067,959 S**
(45) **Date of Patent:** **** Mar. 25, 2025**

(54) **SURVEILLANCE CAMERA**

(71) Applicant: **Dongguan Chemomo Electronic Technology Co., Ltd.**, Guangdong (CN)

(72) Inventor: **Yawu Miao**, Jiangxi (CN)

(73) Assignee: **Dongguan Chemomo Electronic Technology**, Dongguan (CN)

(**) Term: **15 Years**

(21) Appl. No.: **29/903,568**

(22) Filed: **Sep. 25, 2023**

(51) LOC (15) Cl. **16-01**

(52) U.S. Cl.

USPC **D16/203**

(58) **Field of Classification Search**

USPC D10/106.6; D12/164, 172, 412, 415; D14/125, 203.1, 496, 474; D16/200, 202, D16/203, 217, 218

CPC G03B 19/02; G03B 15/05; H04N 23/51; B60R 11/04

(57) **CLAIM**

The ornamental design for a surveillance camera, as shown and described.

DESCRIPTION

FIG. 1 is a first perspective view of a surveillance camera showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1; and,

FIG. 8 is a bottom plan view of FIG. 1.

The broken lines in the drawings depict portions of the surveillance camera that form no part of the claimed design.

1 Claim, 8 Drawing Sheets
